UNITED STATES PATENT OFFICE

CHRISTOPHER EDMUND GERVASE BAILEY, OF LONDON, ENGLAND, ASSIGNOR TO
VICTOR TALKING MACHINE COMPANY, A CORPORATION OF NEW JERSEY

WIRELESS CIRCUITS

Application filed February 25, 1930, Serial No. 431,307, and in Great Britain March 7, 1929.

The present invention relates to wireless circuits such for example as wireless receiving circuits, which comprise two or more tuned circuits.

5 In such circuits it is desirable that the tuning of the tuned circuits should be effected by the operation of one control. A difficulty is experienced in adapting such a single-controlled circuit for use with aerial 10 systems of different capacity, owing to the capacity to earth of the aerial shunting the inductance included in one of the tuned circuits.

An object of the present invention is to 15 provide means whereby the effect of the capacity to earth of the aerial in one tuned circuit, is compensated for in another tuned circuit thus allowing the tuning of the circuits to be effected by the operation of one 20 control.

According to the present invention this 25 is carried into effect by providing a condenser shunted across a portion only of the inductance in one tuned circuit, a portion only of the inductance in the other tuned circuit being included in the circuit between the aerial and the earth. The inductance of each of these said portions may, with advantage, be made equal. Also, the compensating condenser may be variable so as to 30 admit of its being adjusted when aerials of different capacity to earth are used.

The invention is illustrated in the accompanying drawing by way of example as 35 applied to a wireless receiver embodying one stage of high frequency amplification and a detector.

One tuned circuit comprises an aerial tuning inductance 1 having a variable condenser 2 connected in parallel therewith. One end of this inductance is connected to the grid of the first valve 3, which acts as a high-frequency amplifier and is of the screen grid type, the other end being earthed. The 40 aerial 4 is connected to a tapping point 5 on the inductance 1, situated at a distance from the earthed end approximately equal to one quarter of the total length of the inductance. The second tuned circuit, which serves as a 45 coupling between the first valve 3 and a sec-

ond valve 6, which in this case is a detector, comprises a second inductance 7 having a variable tuning condenser 8 connected in parallel therewith, one end of this inductance being connected through a condenser 9, to the anode of the first valve 3 and, through a condenser 10, to the grid of the second valve 6, the other end of the inductance 7 being connected to earth and to the filaments of the two valves. The anode of the valve 3 is connected through a high frequency choke coil 11 to the positive terminal of a high tension source, the negative terminal of which is earthed. The screen grid of the valve 3 is also connected to a suitable point on this source. A variable condenser 12 which acts as a compensator is tapped across a portion of the second inductance 7, the inductance of this portion equaling that of the portion of the aerial tuning inductance 1 shunted by the capacity to earth of the aerial 4. The capacity of the condenser 12 is made equal to this capacity to earth of the aerial, and remains fixed at this value. The two tuning condensers 2 and 8 are mechanically interconnected, or ganged, so that tuning can be effected by the operation of one control.

The anode circuit of the valve 6 may be connected in any known or suitable manner 80 to a reproducing device or to a low frequency amplifier.

The invention can clearly be applied to circuits comprising more than two tuned circuits, such, for example, as a multi-stage high frequency amplifier, in which case the effect of the capacity between the earth and the aerial, which capacity is in shunt with a portion of the inductance in one tuned circuit, may be separately compensated for in each of the other tuned circuits in the manner described above.

I claim:

1. A wireless circuit comprising two tunable oscillatory circuits wherein a portion only of the inductance in one of said tunable circuits is included in the circuit between the aerial and earth terminals, characterized by the fact that a condenser is 100

shunted across a portion only of the inductance in the other tuned circuit.

2. A wireless circuit according to claim 1, characterized by the fact that said portions are substantially equal.

3. A wireless circuit according to claim 1, characterized by the fact that the said condenser is a variable condenser.

4. A wireless circuit according to claim 1, characterized by the fact that the tuning controls for said tunable circuits are interconnected.

5. In a signal amplifying system, a plurality of tunable circuits, means for simultaneously tuning said circuits and variable means connected directly in shunt to a portion of one of said circuits for compensating the detuning of another of said circuits by the connection thereto of an antenna.

6. In a signal amplifying system, a thermionic device having an input inductor, means for connecting spaced apart points on the inductor respectively to an antenna and to a counter-capacity, an output inductor connected to said device, said inductor also serving as an input inductor for a succeeding thermionic device, means for simultaneously tuning said inductors, and means associated with the output inductor for compensating for the electrical characteristics of an antenna, said means including a variable impedance device connected directly in shunt to a portion of the output inductor, whereby true unicontrol may be had irrespective of the connection to the input inductor of differing antennæ.

7. In a signal amplifying system, a plurality of tunable circuits, a tuning inductance in each of said circuits, means for simultaneously tuning said circuits, and variable means connected directly in shunt to a portion of the tuning inductance of one of said circuits for compensating the detuning of another of said circuits by connection thereto of a signal input circuit.

In testimony whereof I have signed my name to this specification.

CHRISTOPHER EDMUND GERVASE BAILEY.
